UNITED STATES PATENT OFFICE.

NIKOLAUS KESSLER, OF RAGUSA, AUSTRIA-HUNGARY.

ELECTRIC ALARM-BELL.

No. 909,192.

Specification of Letters Patent.

Patented Jan. 12, 1909.

Application filed May 27, 1907. Serial No. 375,852.

To all whom it may concern:

Be it known that I, NIKOLAUS KESSLER, a subject of the Emperor of Austria-Hungary, residing at Ragusa, Dalmatia, Austria-Hungary, have invented new and useful Improvements in Electric Alarm-Bells, of which the following is a specification.

This invention has for its object an electric alarm bell, the essential feature of which consists in the bell hammer being held by two spring arms, on the ends of which an armature is provided, under which an electromagnet is located, which is connected with a conducting wire of the bell, so that, on the electric circuit being closed the electromagnet attracts the armature, the spring arms release the bell hammer and the latter, in consequence of the current flowing through the electromagnet of the bell, only then gives the warning signal, with the object of avoiding any unintentional ringing of the bell in consequence of shaking or other vibration.

One form of construction of the invention is shown as an example in the accompanying drawings; in which:—

Figure 1 is an elevation of the bell; and Fig. 2, a detail of the same.

According to this invention, an electric bell is provided with a device which prevents the unintentional ringing of the bell in consequence of shaking or any other vibrations. To this end the bell hammer 1 is held by two spring arms 2, on the ends of which

an armature 3 is provided, under which an electromagnet 4 connected with the conducting wires of the bell, is located. When, therefore, the electric circuit is closed, the electromagnet 4 attracts the armature 3, the spring arms 2 leave the bell hammer 1 free and the latter, in consequence of the current flowing through the electromagnet of the bell, gives a warning signal. After the circuit is opened the spring arms 2 return to their original position and hold the striking hammer 1 of the electric bell fast.

Having now particularly described and ascertained the nature of my invention, what I claim as new and desire to secure by Letters Patent is:

In combination with a bell and a bell hammer, two spring arms, restraining said hammer, an armature on the active ends of said arms, an electromagnet located under said armature and conductor making circuit through said magnet so that on the circuit being closed the electromagnet attracts the armature, the spring arms release the hammer and then only the latter gives the warning signal, avoiding accidental ringing of the bell substantially as set forth.

In testimony whereof I affix my signature in presence of two witnesses.

NIKOLAUS KESSLER.
